GARAGE DOOR LATCH AND LOCK

Filed June 9, 1941

INVENTOR:—
HERBERT G. HONIG.
BY Martin P. Smith, ATTY.

UNITED STATES PATENT OFFICE

2,329,348

GARAGE DOOR LATCH AND LOCK

Herbert G. Honig, Los Angeles, Calif.

Application June 9, 1941, Serial No. 397,242

1 Claim. (Cl. 292—125)

My invention relates to a combined latch and lock for garage doors, particularly those types of doors that are mounted to swing from a vertically disposed position when closed into a horizontally disposed position in the upper portion of the door opening and vice versa, and the principal object of my invention is to provide relatively simple, practical, and inexpensive latching means for effectively maintaining the door in closed position and which latching means may be readily released to permit the door to be opened by manually operable means, a part of which is located on the external face of the door.

A further object of my invention is, to combine with a garage door latching device of the character referred to, simple and efficient locking means, the same being associated with the manually operable means that is utilized for releasing the latch.

A further object of my invention is, to provide a combined latch and lock for garage doors wherein a keeper anchored in the garage floor is engaged by rigid and movable latching means when the door is closed, thus positively securing the door in closed position until the movable member of the latching means is disengaged from the keeper as a result of actuation of the manually operable releasing means located on the exterior of the door.

A further object of my invention is, to provide a garage door latch and lock of the character referred to, of strong and substantial construction, capable of being readily installed upon the door and comprising few parts, thereby minimizing the possibility of the device becoming inoperative after being properly installed.

With the foregoing and other objects in view, my invention consists in certain novel features of construction and arrangement of parts that will be hereinafter more fully described and claimed and illustrated in the accompanying drawing in which:

Fig. 1 is a vertical section taken through the center of a garage door and showing the same equipped with my improved latch and lock.

Fig. 2 is an elevational view of the latch as seen looking in the direction indicated by the arrow 2 in Fig. 1 and showing a portion of the garage floor in section.

Fig. 3 is a vertical section taken on the line 3—3 of Fig. 2.

Fig. 4 is a horizontal section taken on the line 4—4 of Fig. 3.

Fig. 5 is an enlarged horizontal section taken approximately on the line 5—5 of Fig. 1.

Referring by numerals to the accompanying drawing which illustrates a preferred embodiment of my invention, 10 designates a garage door of conventional construction and by means of arms 11 secured to the inner face of the door and pivoted at 12 to suitable supports within the garage, this door is adapted to swing from its normally closed vertical position upwardly and inwardly to a substantially horizontal position in the upper end of the door opening as shown by dotted lines in Fig. 1.

A keeper 13, preferably of metal and provided with a horizontally disposed opening 14, is positioned on the surface of the garage floor which is usually formed of concrete, and to anchor this keeper in position an integral stud projects from the under side of said keeper downwardly into the floor and said stud being provided with a head 14a and an aperture 15. The top 16 of the keeper or that portion above the opening 14 is inclined toward the door opening and the inner or forward edge of said inclined upper portion is rounded or beveled as designated by 17.

Rigidly fixed to the inner face of the door 10 immediately above its lower edge is a metal plate 18 with which is formed integral a pair of ears 19 and passing through said ears is a pin or bolt 20 that is retained in position by means of a cotter pin 21.

Journalled on the pin or bolt 20 between the ears 19 is a short horizontally disposed arm 22 provided on its free end with a depending hook 23 and the end of this hook when the door is closed, projects into the opening 14 in keeper 13 beneath the inner portion of the upper part 16 of said keeper.

Passing around pin or bolt 20 between the arm 22 and one of the ears 19 is the coiled portion of a spring 24, one end of which bears against plate 18 and the other end bearing against a shoulder 25 on the side of arm 22, thereby tending to force the free end of the arm 22 downwardly and consequently maintaining the hook 23 beneath the upper member 16 of the keeper.

Formed integral with the lower end of plate 18 is an outwardly projecting lug or finger 26 which when the door is closed, projects into the rear portion of the opening 14 in the keeper opposite from the pivoted hook 23. Thus when the latch is engaged with the keeper, the lug or finger 26 prevents the door from being opened by inserting a lever or the like beneath the lower edge of the door and prying the same upwardly and the hook 23 prevents the lower portion of the door

from being pried or pulled outwardly away from the door opening.

Formed through the door a suitable distance above the latch is a bearing 21 for a horizontally disposed shaft 28 and mounted on the inner end of said shaft is a short crank arm 29. The lower end of a member 30, for instance, a cable, wire, chain, or a metal rod or tube, is loosely connected to an eye 31 that is formed on the end of arm 22 above the hook 23, and the upper portion of this member is provided with a loop 32 that passes around the wrist pin of the crank 29.

A retractile spring 30a is connected to the end of crank arm 29 and to the garage door at a point a substantial distance below the shaft 28 and which spring cooperates with spring 24 in returning the hook 23, member 30, and crank arm 29, to their normal positions after having been actuated to release the hook from the keeper 13.

When the latch is in engagement with the keeper 13, the crank arm occupies a vertical position as illustrated in Fig. 1.

Shaft 28 projects a short distance outwardly through the door 10 and loosely mounted on said projecting portion is a handle 33 having associated therewith a short housing 34 that encloses a conventional key operated lock of the type wherein the insertion and manipulation of the key locks the handle to shaft 28.

Locking handles of this type are extensively used on the doors of motor vehicles.

When the garage door provided with my combined latch and lock is closed, the lug or finger 26 and hook 23 enter the opening 14 in the keeper 13, thus securely maintaining the door in closed position, and to lock the door it is only necessary to manipulate the lock associated with the handle 33 by means of the key, so that the handle is disconnected from the shaft 28 and thus manipulation of the handle will not rotate shaft 28 to release the latch.

To release the latch, the lock is manipulated by means of the key so as to establish a driving connection between the handle 33 and shaft 28 and as the handle is now swung through an arc of approximately ninety degrees, the crank arm 29 will be swung upwardly a corresponding distance, thereby pulling member 30 upward and swinging the hook-carrying arm 22 upward so as to disengage hook 23 from the keeper.

With the parts so positioned, the door can be swung outwardly, upwardly, and then inwardly to its open position as shown by dotted lines in Fig. 1.

5 When the door is swung from open to closed position, the hook 23 rides upward over the inclined upper surface of the member 16 of the keeper and after passing the rounded inner edge 17 of said upper portion, the hook will under the influence of spring 24 move downward so that its end projects into the opening 14 of the keeper, thereby latching the door in closed position.

Thus it will be seen that I have provided a garage door latch and lock that is relatively simple in construction, inexpensive of manufacture and very effective in performing the functions for which it is intended.

It will be understood that minor changes in the size, form and construction of the various parts of my improved garage door latch and lock, may be made and substituted for those herein shown and described, without departing from the spirit of my invention, the scope of which is set forth in the appended claim.

I claim as my invention:

A garage door latch comprising a keeper adapted to be anchored in the floor beneath the door, which keeper is provided with a horizontally disposed opening and an inclined upper surface the forward upper edge of which is rounded, a plate adapted to be secured to the inner face of the lower portion of the garage door, a lug projecting horizontally from the lower portion of said plate and adapted to enter and occupy the rear portion of the opening in the keeper when the door is closed said lug being wedge-shaped in longitudinal section, an arm pivoted to said plate above said lug, a spring associated with said plate and arm for resisting upward swinging movement of the latter, and a hook projecting downwardly and inwardly from the outer end of said pivoted arm which hook is provided with a curved outer face which engages and rides over the inclined upper surface and rounded forward edge of said keeper as the door approaches full closed position thereby swinging the arm and hook upward so that the latter may enter the forward end of the opening in the keeper when said door is fully closed.

HERBERT G. HONIG.
